(57) **CLAIM**

We claim the ornamental design for patterned material for body wear and gear, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of patterned material for body wear and gear, showing our new design, wherein the design is embodied in a jacket;

FIG. 2 is a front view of patterned material for body wear and gear, wherein the design is embodied in a shirt;

FIG. 3 is a front view of patterned material for body wear and gear, wherein the design is embodied in a jacket;

FIG. 4 is a front view of patterned material for body wear and gear, wherein the design is embodied in a sleeping bag;

FIG. 5 is a front view of patterned material for body wear and gear, wherein the design is embodied in a shoe;

FIG. 6 is an enlarged front view of the claimed region of FIGS. 1-5;

FIG. 7 is an enlarged perspective view of the region denoted on FIG. 6;

FIG. 8 is a front view of patterned material for body wear and gear, wherein the design is embodied in a jacket;

FIG. 9 is a front view of patterned material for body wear and gear, wherein the design is embodied in a shirt;

FIG. 10 is a front view of patterned material for body wear and gear, wherein the design is embodied in a jacket;

FIG. 11 is a front view of patterned material for body wear and gear, wherein the design is embodied in a sleeping bag;

FIG. 12 is a front view of patterned material for body wear and gear, wherein the design is embodied in a shoe;

FIG. 13 is an enlarged front view of the claimed region of FIGS. 8-12; and,

FIG. 14 is an enlarged perspective view of the region denoted on FIG. 13.

(Continued)

The dot-dot-dash broken lines adjacent to the shaded area represent boundaries of the claimed design and form no part of the claimed design. The broken lines depicting the remainder of the patterned material for body wear and gear show features that form no part of the claimed design. While the color of the gold elements forms an element of the claimed design, the color of the background material of the body wear and gear forms no portion of the claimed design.
